UNITED STATES PATENT OFFICE.

JOSEPH HYSON WIEHL, OF ZELIENOPLE, PENNSYLVANIA, ASSIGNOR OF ONE-THIRD TO WM. M. C. JONES, OF PITTSBURG, PENNSYLVANIA.

ATTACHMENT FOR GAS-ENGINES.

SPECIFICATION forming part of Letters Patent No. 608,944, dated August 9, 1898.

Application filed April 21, 1897. Serial No. 633,098. (No model.)

To all whom it may concern:

Be it known that I, JOSEPH HYSON WIEHL, a citizen of the United States, residing at Zelienople, in the county of Butler and State of Pennsylvania, have invented certain new and useful Improvements in Attachments for Gas-Engines; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to certain new and useful improvements in an attachment for gas-engines.

The invention pertains to gas or other explosive-power engines. Engines of this class 20 possess numerous defects, some of which are here mentioned, and which this invention is designed to overcome, among which are—

First. Gases of any description when exploded in the cylinder produce great heat, 25 which is absorbed by all parts connected thereto. This has been overcome to some extent by forming water-jackets around the cylinder and heads of the same, through which water is caused to circulate, but with 30 little success, as the internal parts of the cylinder, where the heat is generated, become heated to a high degree, producing unequal expansion of parts, causing increased friction and considerable loss of power and wear upon 35 the working parts.

Second. Oils introduced into the cylinders of the gas-engines give very poor results by reason of the heated condition of the cylinder, and instead of acting as a lubricating 40 agent frequently cause trouble by charring and causing friction.

Third. The main object of the builders of gas-engines has been to produce a gas-engine which would be capable of giving a perfect 45 impulse at each end of the cylinder and at every stroke, which is of considerable importance where regular speed is required. Some builders claim a perfect explosion in their particular class of engines at each revolution, 50 whereas it only takes place at intervals, as any mixture of gas and air at a moderate tem-

perature will enter in perfect volume and proportions into a cylinder only at intervals.

Fourth. Another objectionable feature in the present gas-engine is the loud report of 55 the exhaust as it escapes from the cylinder, and the method now employed is to turn the exhaust into tanks, &c., which is not only an additional expense, but causes a back pressure in the cylinder and loss of power, and 60 thus greatly retards, both by heat and pressure, the explosion of the gas in the cylinder at the proper time.

Fifth. By reason of untimely explosions in 65 gas-engines all castings and foundations are constructed exceptionally heavy or of great strength to withstand the great pressure brought to bear upon them by over-accumulated bodies of gas of sufficient volume for several strokes or revolutions, but which frequently explodes at one impulse, thus requiring unnecessary heavy parts of the machine. Furthermore, it is a well-known fact that 70 when gas-engines are working heavy a solid sheet of flame is forced out through the exhaust-pipe to a considerable distance from the explosion, which is a waste of power and energy which, properly utilized, would effect a saving in gas. Therefore the object of my invention is to modify and correct the above- 75 described defects by attaching my improved device to the cylinder-head of the engine, and which I term an "animator," and which consists of a cylinder provided with an internal piston which is adapted to be operated 80 and cause a fine spray of water to be introduced into the cylinder at the time of the explosion by the pressure at each explosion 85 of gas within the engine-cylinder.

The said piston-head is provided with a 90 hollow piston-rod having a valve arranged therein and which enters into a chamber containing water, which is supplied thereto from a tank provided with a suitable check-valve and a pipe leading from the tank and connecting to the chamber. The working parts 95 of and the construction of the device will be fully shown and described in detail.

In describing the invention in detail reference is had to the accompanying drawings, 100 forming a part of this specification, wherein like numerals designate like parts, in which—

Figure 1 is an end view of my improved device attached to an engine-cylinder. Fig. 2 is a side elevation of the same, partly in section. Fig. 3 is a side sectional view of the 5 piston with its valve arranged therein. Fig. 4 is an end view of the same. Fig. 5 is an end view of the valve removed.

Referring to the drawings, the numeral 1 designates a gas-engine cylinder of ordinary 10 construction, and the numeral 2 designates the head of the same and which is provided with an opening 3.

4 is a circular flanged check-plate which has an opening formed within its central portion and is provided with a flanged extension portion 5, which extends a short distance into the said opening of the cylinder-head. Fitted onto the outer face of the said check-plate is the air-cylinder 6, which is secured to the engine-cylinder head by the bolts 7.

Secured to the opposite end of the said air-cylinder and by the bolts 8 is the water-chamber 9. Fitted into the opposite end of the water-chamber is the shouldered nut 10, which 25 forms a head for that end of the chamber. Upon the upper portion of the water-chamber is formed the projecting boss 11, which is provided with an opening or inlet communicating with the interior part of the chamber 30 and has fitted or connected to its upper end the pipe 12, which leads from the water-supply; or if the engine is of the upright pattern a more direct water-supply may be obtained by removing the screw-nut 10 and connecting the supply-pipe to that end of the chamber and by plugging up the inlet 11. A drain-cock 18 is connected to the underside of the chamber, so that the water may be drained from the chamber through the opening 19 when required. A double piston-head 20 and 20' is fitted into the air-chamber and is formed upon or attached to the hollow piston-rod 21. The said piston-rod extends into the water-chamber at one end, and the 45 opposite end extends into the engine-cylinder. An enlarged portion 21' is formed upon the said piston-rod and extends part way into the opening of the check-plate. Within that end of the said piston-rod which extends 50 into the cylinder-head is secured the hollow spraying cap or nozzle 22, having a series of small openings formed therein, through which the water is sprayed into the cylinder. Fitted into the opposite end of the said piston-rod, 55 which extends into the water-chamber, is the hollow thimble 23, through which the water enters into the piston-rod and has a valve-seat formed upon its inner end.

Within the enlarged chamber portion 60 formed within the piston-rod is loosely fitted the check-valve 24, which is adapted to fit upon the seat formed upon the inner end of the said thimble and has the wings 25 formed thereon and which are adapted to support the 65 valve within the said chamber. The small holes 26, leading from the interior of the piston-rod up through and between the flanged

heads of the piston, are adapted to conduct water from the interior of the rod to the space between the heads, so as to keep them cool. 70 Within the lower side of the air-cylinder is formed the small opening 26 through which the air is supplied to the cylinder, and the telescopic spiral spring 27 is adapted to return the piston to its normal position. 75

The operation of the device would be as follows: Supposing that there had been an explosion in the cylinder of the engine and exhaust and the engine-piston is on the return and is compressing the air and gas for the next impulse, now if this accumulated pressure be allowed to act directly upon the piston-head 20 within the air-chamber it would, by reason of its large "area," cause it to move forward and exhaust the water within the 85 chamber and piston-rod by spraying most of it into the engine-cylinder before the explosion would take place; but as only the face of the enlarged portion 21' of the piston-rod is presented and as the area thereof is only 90 about one-third of the surface area to the accumulated pressure its movement would be correspondingly slow, and at the same time while moving slowly it is forcing a fine spray of water which invigorates and causes a perfect explosion by the component parts of gas, air, and water. When the said explosion takes place, the piston is far enough advanced into the air and water chambers 6 and 9 to allow the pressure from the engine-cylinder 100 to enter that end of the air-chamber and act upon the piston-head 20, forcing the said piston rapidly forward by reason of the large area presented thereon and causing the plunger 21 to enter farther into the water-chamber 105 and displace the water therein, which escapes into the chamber within the piston-rod and out of the opposite end into the fire and heat within the engine-cylinder, where it is instantly converted into steam. After the 110 pressure within the engine-cylinder has been exhausted the spiral spring 27 returns the piston to its normal position and at the same time acts as a pump and fills the water-chamber with a new supply of water. Before the 115 said piston within the air-chamber returns to its normal position a sufficient amount of air enters the said chamber through the small opening 26, so that when the piston returns to its normal position the air will form 120 a cushion between the face of the piston and the check-plate and prevent a sudden blow, and at the same time the said compressed air will aid in operating or forcing the piston back again at the beginning of its next stroke. 125

Slight variations may be made in the detail parts of the invention without departing from the general principle involved.

Having thus fully shown and described my invention, what I claim as new, and desire to secure by Letters Patent, is—

1. In a gas-engine, the combination with the gas-engine cylinder, having an opening in one head, the circular flanged check-plate having

a central opening and a circular flanged extension or boss fitting in said opening, the air-cylinder secured to said check-plate formed with an air-inlet opening, the water-cylinder secured to said air-cylinder, the water-supply pipe and the shouldered nut closing the end of said water-chamber, of the hollow piston-rod, provided with double pistons, with radial openings between the same, the enlarged portion passing through the opening in said flanged check-plate, the spraying-nozzle, the check-valve located in said piston, formed with wings and the spiral spring located in said air-cylinder, substantially as shown and described.

2. The combination with a gas-engine cylinder, having an opening in one head, the air-

cylinder formed with an air-inlet opening, and the water-chamber, of the hollow piston, the ends of which are located in the said water-chamber and engine - cylinder, the heads formed therewith and said piston formed with radial holes between said heads, the spraying-nozzle at one end formed with a flaring opening of said piston, the thimble at the opposite end, the wing-valve located in said piston and the spring located in said air-cylinder, substantially as described.

In testimony whereof I affix my signature in presence of two witnesses.

JOSEPH HYSON WIEHL.
